UNITED STATES PATENT OFFICE.

WILLIAM MILD, OF HAMILTON, OHIO.

MACHINE FOR CUTTING AND GRATING VEGETABLES.

SPECIFICATION forming part of Letters Patent No. 226,096, dated March 30, 1880.

Application filed November 3, 1879.

To all whom it may concern:

Be it known that I, WILLIAM MILD, of Hamilton, in the county of Butler and State of Ohio, have invented certain new and useful Improvements in Machines for Cutting and Grating Vegetables, of which the following is a specification.

My present invention relates to certain improvements in a machine for cutting and grating vegetables for which Letters Patent No. 220,723 were granted to me October 21, 1879; and it consists in providing on the periphery of the disk carrying the cutters a flange or rim turned inwardly and of sufficient width 15 to form the hub or center for the grater, and in making the grater in disk form, with a flange or rim turned on the periphery to fit over and bind on the flange of the cutter-disk.

This arrangement enables me to vary the rate 20 of grating without changing the speed of the machine by shifting the vegetable from the center to the periphery of the disk, or vice versa.

Certain vegetables, to grate well, require a 25 higher speed than others, and this, with my previous machine, could only be obtained by varying the speed of the machine, which, with power-machines, requires expensive gearing or cone-pulleys, all of which are avoided by the 30 present construction.

In the accompanying drawings, Figure 1 is a front elevation of my machine, showing the grater in position on the cutter-disk. Fig. 2 is a front elevation thereof with the grater removed, exposing the cutter-disk and knives. Fig. 3 is a side or end elevation of the machine, showing a cabbage-corer attached to the driving-shaft. Fig. 4 is a perspective view 35 of the cutter-disk. Fig. 5 shows the furrowing-knife detached. Fig. 6 shows the cabbage-corer. Fig. 7 is a sectional elevation of the cutter-disk, and Fig. 8 a sectional elevation of the grater.

A is the stand or frame of the machine, 40 which I make in ornamental style of cast-iron.

On the upper surface of the frame I provide a long box, which is bored for the reception of the driving-shaft b. Upon the back of the frame I cast a boss, which is bored for the reception of the stud e, upon which turns the spur-wheel E, giving motion to the spur-pinion b', driving-shaft b, and cutter-disk B. B is the cutter-disk, of cast-iron, keyed or otherwise secured to the driving-shaft. C is a table secured to the ends of the frame by gibbs, 55 and capable of being easily removed for changing the machine. D is a guard of cast or sheet iron, secured to the upper side of the frame, to prevent particles of vegetables from flying off at a tangent. F is the furrowing-knife, and h the slicing-knife. When the machine is to be used for slicing vegetables, as cabbage, two slicing-knives, as h, are used.

B' is the grater, of disk form, perforated on the face and provided with an annular flange 65 or rim to fit over and bind the rim of the cutter-disk B. G is the corer, for removing the centers of the cabbage.

An inclined shelf is provided in the lower part of the frame, upon which the cut or grated 70 vegetables fall, and pass into any convenient receptacle set below.

Although I show and describe a machine to be operated by hand, it is obvious that a pulley can be placed on the driving-shaft and 75 the machine driven by power.

Having described my invention, what I claim is—

The cutter-disk B, provided with an annular rim turned inwardly, in combination with 80 the flanged grater B', driving-shaft b, and driving-gear E and b', for the purpose and as described.

In testimony whereof I have hereunto set my hand this 25th day of September, 1879.

WILLIAM MILD.
